UNITED STATES PATENT OFFICE.

THOMAS DUNMORE, OF NORWALK, OHIO.

HEATING AND VENTILATING APPARATUS.

SPECIFICATION forming part of Letters Patent No. 421,562, dated February 18, 1890.

Application filed April 8, 1889. Serial No. 306,370. (No model.)

To all whom it may concern:

Be it known that I, THOMAS DUNMORE, a citizen of the United States, residing at Norwalk, in the county of Huron and State of Ohio, have invented a new and useful Heating and Ventilating Apparatus, of which the following is a specification.

This invention relates to an improved system of heating and ventilating churches, school-houses, and other large public halls, as well as private dwellings; and it has for its object to cause a more perfect circulation of air than is readily attained by the ordinary methods now in vogue.

With this end in view the invention consists in the improved construction and arrangement of the heating-radiators, the cold-air ducts, and foul-air flues, which will be hereinafter more fully described, and particularly pointed out in the claims.

In the drawing hereto annexed, which represents a vertical sectional view of a building or structure equipped with my invention, A A designate the walls of the building, and B B the floors, whereby the structure is subdivided in the usual manner.

C designates a furnace, which is preferably located in the basement, and D D are the steam-pipes leading from said furnace to the radiators E E, which are located at convenient points upon the several floors of the building.

Each of the radiators is partially surrounded by a box or casing F, constructed, preferably, of sheet metal, and extending to nearly half the height of the radiators, although it will of course be understood that the relative height of the radiator and its surrounding box or casing may be altered to suit the circumstances of each case. In the flooring below the casings F and communicating with the same are cold-air reservoirs G, which communicate with the outer air through ducts H, constructed, preferably, between the joists of the flooring, although the said cold-air ducts may, when necessary, be in the shape of flues extending through the rooms of the building in any manner which shall be deemed most convenient. The cold-air flues or ducts may be provided at or near their outer ends with valves II' to regulate the admission of cold air.

It will be seen from the foregoing that fresh

and pure cold air may be taken from outside the building and conveyed to the cold-air boxes located below and partially surrounding the radiators, by contact with which the said cold and pure air will be thoroughly heated before it is discharged into the rooms of the building. It will also be seen that the boxes or casings F, which surround the radiators at their lower ends, prevent the cold-air from spreading along the floor of the room before it has become thoroughly heated, and that the very common objection of cold floors is thus to a considerable extent avoided.

I designate the foul-air flues, which are suitably constructed in the several rooms of the building, and which serve to convey the vitiated air from the said rooms to the attic-room R², where the said foul-air flues are provided with self-acting valves J to regulate the escape of the vitiated air. The roof of the building has a ventilator K, through which the foul air eventually escapes. To cause an upward draft in the foul-air flues, I locate within the latter several coils L of steam-pipes, by contact with which the foul air as it enters the said flues becomes heated, thereby causing a strong upward draft or current. The foul air enters the flues I through registers R, located at the floors of the room, the escape of air from which may thus be perfectly regulated.

It will be seen that by the foregoing arrangement of the foul-air flues the vitiated air is discharged into the attic of the building before being allowed to escape. When the foul-air flues open directly into the outer air, even when they are provided with regulating-valves, the draft in said flues is liable to be impaired and interfered with by storms and other atmospheric conditions. Not so by the herein-described construction and arrangement, whereby the vitiated air may, under all conditions of the outer atmosphere, be discharged unobstructedly into the attic, whence it may escape through the ventilator. It will, furthermore, be seen that the self-acting valves J will prevent any possibility of "back-draft," or of the foul air being driven through the flues I back into the rooms by wind-storms, which might otherwise have a tendency to that effect.

It will be seen from the foregoing descrip-

tion that the cold and pure air on being taken from the outside is thoroughly heated before it is discharged upwardly into the rooms. After rising to the ceiling it will be gradually displaced by the fresh air continually entering, and, being furthermore gradually cooled, it will descend in a downward current along the walls of the room, and be attracted to the foul-air registers, owing to the upward draft in the foul-air flues. In this manner an absolutely perfect circulation of the air will be kept up, and the air contained in each room may be removed as frequently as may be desired by properly regulating the entrance and exit valves or registers.

It is obvious that the particular construction of the furnace and the radiators in no way affects the operation and utility of my invention; also, that my invention is applicable to other heating devices than steam-radiators without departing from the spirit of my invention.

Having thus described my invention, I claim—

In heating and ventilating apparatus, the 25 combination of the heating devices, the casings or deflectors surrounding the lower ends of the same, the cold-air reservoirs arranged below and communicating with said casings, the valved ducts connecting said reservoirs 30 with the outside of the building, the attic-room forming a temporary receptacle for ventilating air, the foul-air flues extending into said attic-room, the self-acting valves at the upper or discharge ends of said foul-air flues within 35 the attic-room, the registers at the lower ends of the latter, heating devices arranged in said foul-air flues to cause an upward draft therein, and a ventilator in the roof of the building to carry off the vitiated air from the attic- 40 room, substantially as set forth.

In testimony that I claim the foregoing as my own I have hereto affixed my signature in presence of two witnesses.

THOMAS DUNMORE.
